[57] CLAIM

The ornamental design for a combined bottle and closure, as shown and described.

DESCRIPTION

FIG. 1 is a front elevation of a combined bottle and closure showing my new design, the rear elevation is a mirror image thereof;

FIG. 2 is a right side elevation thereof;

FIG. 3 is a top plan view thereof; and,

FIG. 4 is a top, front and left side perspective view of the combined bottle and closure shown on an enlarged scale.

The bottom of the bottle is plain.

FIG. 1

FIG. 2

FIG. 3

FIG. 4
